UNITED STATES PATENT OFFICE

AUSTIN V. M. SPRAGUE, OF ROCHESTER, NEW YORK, ASSIGNOR TO THE SPRAGUE-SCHUYLER MANUFACTURING COMPANY, OF NEW JERSEY.

STERILIZING APPARATUS.

SPECIFICATION forming part of Letters Patent No. 505,967, dated October 3, 1893.

Application filed August 15, 1892. Serial No. 443,171. (No model.)

To all whom it may concern:

Be it known that I, AUSTIN V. M. SPRAGUE, of Rochester, in the county of Monroe and State of New York, have invented a certain 5 new and useful Improvement in Sterilizing Apparatus; and I do hereby declare that the following is a full, clear, and exact description of the same, reference being had to the drawings accompanying this application.

10 This improvement relates to sterilizing apparatus for surgeons' uses, and is designed, more particularly, for treating fibrous dressings by means of steam and heat.

15 The invention consists in the construction and arrangement of parts hereinafter more fully described and definitely claimed.

In the drawings—Figure 1 is a side elevation of the apparatus. Fig. 2 is an end elevation looking from the right in Fig. 1. Fig. 20 3 is a similar view looking from the left in Fig. 1. Fig. 4 is a longitudinal vertical section of the cylinder in line xx of Fig. 2. Fig. 5 is a vertical cross section in line yy of Fig. 1. Fig. 6 is an enlarged plan view of one of 25 the locking devices of the cover or door.

In this apparatus a receptacle A is employed, consisting of three cylinders a , b , c , located one inside of another with dead air spaces between them. These cylinders are 30 closed at one end by a solid back d , and at the other by a cover or door f , hinged at g so as to be turned down. The door is locked in its closed position by a set of thumb nuts h attached to screws i (Fig. 6). These 35 screws rest in open slots jj formed in the edge of the door and end of the cylinder, and are arranged to turn up and down, the inner ends being provided with journals kk for the purpose. When turned down horizontally, as in 40 Fig. 6, the end of the nut bears against the door and locks it in place. When turned up it frees from the slot and frees the door. This is a simple and convenient fastening, as 45 thereby the door can be tightened in place and can be readily opened. The inner cylinder, a , is entire and contains the water pan l , and the trays m on which the materials to be treated are placed. The other two cylinders, b c , have an opening n in the bottom 50 in which is located the burner B. The edges of this opening are closed between the two

cylinders b c , thus forming a dead air space between them, and the outside of the middle cylinder b is covered with a layer of asbestos or other non-conducting material. This, together with the dead air spaces effectually prevents the escape of heat. 55

The burner B is of such form as to fit closely in the opening n and bring the flame in direct contact with the inner cylinder a , 60 and the space between the cylinders a b forms a flue through which the products of combustion pass upward at the top and escape through a chimney o . The heat thus surrounds the whole of cylinder a and heats the 65 chamber to a high degree.

The water receptacle l is at the bottom of cylinder a , and is very shallow, by which means the water is readily converted into steam, and this steam rising in the chamber 70 becomes highly heated and to such a degree that it is practically superheated and becomes dry.

The trays m —one or more—consist preferably of thin metal sheets perforated to allow ready passage of the steam and heat, and they are supported above the water by any suitable means—that shown in the drawings consisting of a removable skeleton frame of hoop or band iron p , provided with lugs which 75 rest under the trays.

r (Figs. 1 and 3) indicates a nozzle which enters the cylinder at the rear end and opens to the interior. To this is attached a T connection outside, provided on one side with a 85 blow off s , and on the other with an air inlet valve t , and in the center with a thermometer v .

In use the fibrous material to be treated is placed on the trays, water is placed in the 90 chamber and heat is applied outside. Wet steam is generated under the first action of the heat. This wet steam saturates the bandages, causing them to open and expand, and thoroughly filling them with water. As the 95 heat increases the steam grows hotter and drier, and coming in contact with the dry heated sides of the chamber it becomes practically superheated. This results from the direct contact of the flame with the inner cylinder a , and the passage of the heat up 100 through the flue and around the whole top of

the cylinder, thus making the top as hot as the bottom and equalizing the temperature throughout. This hot and dry steam coming in contact with the bandages dries them out 5 and leaves them in soft and pliable condition best for use.

The water pan is made integral with the cylinder, and is provided at its outer end with a vertical flange *u* which holds the water and prevents escape through the door. Preferably the water is inserted in charges 10 through the open door, but if desired feed and discharge pipes may be carried through the cylinder for the purpose of supplying 15 and discharging the water. The cylinder is supported by suitable legs *w w*.

It is obvious that the receptacle A might be made effective with the use of two cylinders instead of three. The same flue space for 20 the upward passage of the heat around the inner cylinder would be made and the result would be the same. Three, however, are more effective than two, as the third cylinder excludes the contact of cold air.

25 It is of special importance in my improved construction that excess of air be excluded from circulation about the inner cylinder and that exterior radiation be prevented. Otherwise a sterilizing temperature and a proper 30 dryness of the steam cannot be secured. Radiation is preferably prevented by the double wall inclosing a dead air space though a single wall protected thoroughly by a non-conducting cover of asbestos or the like would 35 operate to secure a like result. The burner is situated in the opening in this outer cylinder in manner to exclude air from passing outside of it and so that the amount required for thorough combustion is introduced in the 40 midst of the gas supply, previously mixed by preference with a small portion of air. The burner in the present instance is shown as made larger than half the length of the cylinders and should in practice be longer rather than shorter. The air inlets may be in the 45 form of nipples and have their upper openings in close proximity to the burner opening whereby the commingling of the mixed air and gas with the requisite additional amount 50 of air is made very thorough, and all necessity for the admission of air in excess is effectually precluded. The gas thus twice mixed with air is forced through fine burner perforations and burned in immediate contact 55 with the water pan in the inner cylinder. The products of combustion are kept in close contact with said cylinder by the enveloping cylinder and are spread out and around the inner cylinder in a thin sheet of uniform thickness and in manner to thoroughly heat said cylinder. The escape pipe is by preference cen-

trally located as shown. The steam generated by these means will be uniformly exposed to heat conducted through the major part of the cylindrical surface of receptacle 65 *a* and will be hot and dry and suitable for sterilizing articles placed on the supporting trays.

Having described my invention, what I claim as new, and desire to secure by Letters 70 Patent, is—

1. In a sterilizing apparatus the receptacle comprising the inner cylinder and an inclosing cylinder arranged to leave a narrow circumferential space between said cylinders 75 said latter cylinder being provided with a covering to prevent radiation and with an exit *o*, in combination with an air mixing burner seated in and substantially filling an opening in the outer cylinder immediately 80 below the inner one and adapted to exclude the passage of air in excess, substantially as set forth.

2. In a sterilizing apparatus the receptacle comprising the inner cylinder and an inclosing cylinder arranged to leave a narrow circumferential space between said cylinders said latter cylinder being provided with a covering to prevent radiation and with an exit *o*, in combination with an air mixing 85 burner seated in and substantially filling an opening in the outer cylinder immediately 90 below the inner one and adapted to exclude the passage of air in excess, said burner having a chamber for mingled air and gas, air inlet nipples and burner perforations; substantially as set forth.

3. In a sterilizing apparatus the inner cylinder provided with a water pan *l* formed by a partition *u*, the surrounding cylinder having a non-radiating cover, and an exit pipe, a burner fitting an opening in the bottom of the latter cylinder, a door hinged to the bottom of said cylinder, and means for tightly clamping said door to the same, substantially 100 as set forth.

4. A sterilizer consisting of a cylinder having means for permitting access thereto and for the retention of a limited quantity of water, a non-conducting jacket with the chamber, a narrow flue provided with an outlet, and a relatively large air and gas mixing burner situated at the lower portion of the said flue, substantially as set forth.

In witness whereof I have hereunto signed 115 my name in the presence of two subscribing witnesses.

A. V. M. SPRAGUE.
